UNITED STATES PATENT OFFICE.

CHARLES J. NASH, OF CHICAGO, ILLINOIS, ASSIGNOR TO UNIVERSAL DRAFT GEAR ATTACHMENT CO., A CORPORATION OF ILLINOIS.

DRAFT-GEAR YOKE.

1,292,358.

Specification of Letters Patent. Patented Jan. 21, 1919.

Application filed February 5, 1913. Serial No. 746,321.

To all whom it may concern:

Be it known that I, CHARLES J. NASH, a citizen of the United States, and resident of Chicago, county of Cook, and State of Illinois, have invented certain new and useful Improvements in Draft-Gear Yokes, of which the following is a specification, and which are illustrated in the accompanying drawings, forming a part thereof.

10 The invention relates to yokes especially adapted for use in connection with so called tandem draft gears for railway cars; that is to say, gears in which a plurality of springs or other shock absorbing elements are employed and are longitudinally alined.

15 The object of the invention is to provide positive buffing connection between the butt of the coupler shank and the yoke, other than any means such as keys or rivets which 20 may be employed for attaching these elements together, and it consists in a yoke having a shoulder against which the butt of the coupler shank bears.

The invention is illustrated in the accompanying drawings, in which—

Figure 1 is a plan view of the draft gear, partly in section, as applied to a car.

Fig. 2 is a detail longitudinal vertical section on the line 2—2 of Fig. 1, and

30 Fig. 3 is a transverse section of the yoke on the line 3—3 of Fig. 2.

There is shown in the drawings portions of the center sills 10, 11, of a railway car and to which are secured draft plates 12, 13, of any desired construction. The coupler is represented at 14 and as being attached by means of a key, 15, to the yoke, 16, which is shown as of the conventional M. C. B. type with cheek plates for the accomodation of 40 the attaching key.

The shock absorbing elements are here represented as a pair of springs, 17, 18, inclosed within the yoke and longitudinally alined, each of the springs being located between a pair of followers, 19, 20, and 21, 22, 45 which coöperate with suitable shoulders on the draft plates 12, 13.

The yoke, 16, is provided with a bridge, 23,

uniting its longitudinal members and located between the rearward of the forward pair of followers and the forward of the rearward pair. The yoke is also provided with a pair of instanding forwardly facing shoulders, 24, 25, formed on its longitudinal members and located substantially in the plane of the forward face of the forward follower, 19, when the gear is in the central position. The butt 26, of the coupler, 14, extends beyond the top and bottom of the follower, 19, and bears against the shoulders, 24, 25. The key, 15, fits loosely but without material lateral movement within the apertures formed in the cheek plates of the yoke and the butt of the coupler for its reception.

Buffing shocks are transmitted through the coupler directly upon the forward follower, 19, and through the shoulders, 24, 25, the longitudinal members of the yoke, and its bridge, 23, to the follower, 21. The key, 15, is, therefore, not called upon to perform any 60 duty in the transmission of such shocks, thereby preventing its distortion, and, also, relieving the cheek plates of the yoke from the violent shocks of impact. Inasmuch as buffing stresses are very much more severe 65 than stresses incident to pulling, the construction shown and described permits of the employment of a lighter key and of lighter cheek plates than are necessary when the buffing action is transmitted through these 70 parts.

I claim as my invention—

A draft gear yoke comprising longitudinal members, a rear end and an intermediate bridge both uniting the longitudinal members, side plates uniting the forward ends of the longitudinal members and forming therewith a throat for loosely receiving the butt of a coupler, the longitudinal members having forwardly facing shoulders in 80 line with their body portions for engagement by the rear face of the coupler butt.

CHARLES J. NASH.
